D. W. CAMPBELL.
DOOR OPERATING MECHANISM.
ORIGINAL FILED DEC. 22, 1920.

UNITED STATES PATENT OFFICE.

DAVID W. CAMPBELL, OF MINNEAPOLIS, MINNESOTA.

DOOR-OPERATING MECHANISM.

Application filed December 22, 1920, Serial No. 432,428. Renewed May 18, 1922. Serial No. 562,041.

To all whom it may concern:

Be it known that I, DAVID W. CAMPBELL, a citizen of the United States, residing at Minneapolis, in the county of Hennepin and State of Minnesota, have invented certain new and useful Improvements in Door-Operating Mechanism; and I do hereby declare the following to be a full, clear, and exact description of the invention, such as will enable others skilled in the art to which it appertains to make and use the same.

This invention relates to a door operating mechanism, and particularly, to such a mechanism which is automatically controlled by a motor.

It is an object of this invention to provide a door operating mechanism that is actuated by an air motor, which motor is controlled by suitable electrical devices.

It is a further object of this invention to provide such a door operating mechanism which will be locked with the doors either in closed or open position and will remain in such locked position until again actuated by the electrical controller.

It is another object of the invention to provide such a mechanism in which the momentum or inertia of the moving door is utilized to co-operate with the motor so that the door opening and closing operation takes place in one cycle of operation of the air motor.

These and other objects and advantages of the invention will appear from the following description made in connection with the accompanying drawings in which like reference characters refer to the same parts throughout the different views and in which,

Fig. 1 is a bottom plan view of the device showing the doors to be operated in section;

Fig. 2 is a view in side elevation of the device showing the same attached to a ceiling, the connection to the doors not being shown; and

Fig. 3 is a partial longitudinal section of one end of the air cylinder.

The invention herein described is an improvement in part upon the mechanism disclosed and claimed in the patent to Steffes No. 1,301,757, granted April 22nd, 1919, to which patent references may be had for details of some of the parts herein generally illustrated.

Referring to the drawings, the doors to be opened are shown in horizontal section as 1 and 2. The complete doors thus comprise a pair of hinged doors, each of which is composed of the members 1 or 2, which members are respectively hinged by the hinges 3 and 4. A stop member 5 is shown with which the doors contact when in closed position.

The door operating mechanism proper is preferably connected to the ceiling or above the top of the doors, as illustrated in Fig. 2. This mechanism comprises a cylinder 6 in which slides a plunger 7 connected to a plunger rod 8. The plunger 7 is adapted to be reciprocated in the cylinder 6 by air or other suitable fluid pressure and the cylinder is connected to some convenient source of compressed air or fluid supply by the connecting means or pipe 9. A controlling valve mechanism is shown, generally, at 10, to which the air supply pipe 9 is connected. This valve mechanism is similar to that shown in the patent above referred to which is connected between the pipes 31, 59 and 60, and is here not shown in detail. This valve mechanism is controlled by a lever 11, which lever is moved laterally by a solenoid 12 which includes an electrical circuit comprising the conductors 13, which circuit is controlled by a push button 14. A rod 15 is connected at one end to a member 16 which engages and is moved by the valve controlling lever 11 when the same is moved laterally. This rod 15 is connected at its other end to a bell crank lever 16. This bell crank lever is pivoted to and carried by a bracket 17 depending from the ceiling or other convenient support, and this bracket also comprises a depending lug 17a which comprises a support and guide for the outer end of the plunger rod 8. The bell crank lever 16 carries, at the end of one of its arms, which arm is normally disposed in substantially horizontal position, a grooved roller member 18. This roller member has its groove, which is centrally located therein, disposed to normally engage the end of a flat bar 19 which is supported at one end by a bracket 20 having a ring thereon which is attached to the plunger 8 by a set screw or other suitable clamping means. The other end of the rod 19 is beveled at an angle of substantially 45 degrees and is supported near its beveled end by a rod 21 riveted or

110

otherwise secured thereto, the other end of which rod is fastened to a crosshead 22 which is clamped and secured to the plunger rod 8. The crosshead 22 extends to each side 5 of the rod 8 and has pivoted at its ends, links 23. These links comprise rods of considerable extent which are pivoted at their other ends to brackets which are, in turn, bolted to one of the doors 1 or 2 and, as illustrated, to the outer one of these doors. The bell crank 16 is normally held in the position shown in Fig. 2 and will tend to resume this position by the action of springs 16^a and 16^b which are connected to the ends thereof 10 and to the ceiling or other support shown.

As above stated, the details of the air controller valve for the cylinder are not herein shown, the same being illustrated in the patent above referred to. In Fig. 3, 20 however, the air controller in the end of the cylinder is shown, which differs from that shown in the said patent. In this figure, the cylinder head 24 is connected to the inlet pipe 25 and the air enters the end of the cylinder 25 behind the piston through ports 26 and 27. The port 28 is also shown, which is similar to that shown in the patent. In the cylinder 24, a port 29 is shown as communicating with the chamber which contains the ball 30 check valve 30, and this port 29 communicates with another port 31 which, in turn, enters and communicates with a port 26. With this structure, when the plunger or piston 7 passes the port 28, the air will be cut 35 off and escape through this port and will tend to pass out through the port 27. The ball valve 30 will prevent said air from passing into the port 26 so that said air must pass through the small port 29 and then 40 through the port 31 to enter the exhaust pipe 25. A screw 32 is shown which can be turned to regulate the opening from port 29 into port 31. The speed at which the air can exhaust from the end of the cylinder 45 after the valve 28 has been closed can thus be regulated by adjustment of the screw 32. With this structure, the movement of the plunger or piston 7 to the end of the cylinder can be nicely regulated and the doors will 50 thus be brought to open or closed position gently and without undue jar or shock. In the present embodiment of the invention, the structure shown in Fig. 3 is used only at the right hand end of the cylinder, as shown in 55 Figs. 1 and 2. At the left hand end of the cylinder, the port 27 is continued to communicate directly with the pipe 25 and the ball check valve and relief passages are omitted.

60 The operation of the device is as follows:

Assuming that the doors are in closed position, as shown in Fig. 1, and the other parts of the device also as shown in Figs. 1 and 2, the plunger rod 8, and bar 19 are held 65 against longitudinal movement by engage-

ment of the roller 18 with the end of bar 19. To open the doors, the button 14 will now be pressed. This will actuate the solenoid 12. The lever 11 will be pulled to the left, as shown in Fig. 1. This movement of the lever 70 11 will move rod 15 to the left and swing bell crank 16 so that roller 18 is swung downwardly off the end of bar 19. This movement of lever 11 will also admit air into the right hand end of cylinder 6 and plunger 7 75 15 will move to the left, together with rod 19, and the roller 18 will roll into engagement with the bottom of the bar 19. The cross-head 22 is also moved to the left and the links 23 will fold the doors, 80 1 inwardly, as indicated by dotted lines in Fig. 1, and the doors 2 will be similarly moved. This movement will continue until the roller 18 reaches the end of bar 19. When the roller passes beyond the end of the rod, 85 it will be raised by the action of springs 16^a and 16^b. At this time, the doors 1 and 2 have been folded and pulled by the links 23 so that the same are approximately in alignment with said links or on a dead center. 90 The momentum of the swinging doors will, however, move the doors beyond this position. At this time, plunger 7 is also approximately at the end of its stroke. When the roller 18 passes the end of rod 19 it will 95 be moved upward to the level or plane as illustrated in Fig. 2. This will move the rod 15 to the right and place the lever 11 in neutral position so that the air is shut off from the right hand end of the cylinder. As 100 the doors swing by their inertia or momentum past the dead center, the links 23 are pulled slightly to the right. This movement will move the bar 19 to the right and the beveled end thereof will cam the roller 105 18 upwardly so that the same will ride on the top of bar 19. This movement will further move the rod 15 to the right and admit air into the left hand end of the cylinder. The plunger 7 and piston rod 8 then immediately 110 start to move to the right and the doors 1 and 2 having swung past the dead center, or the position of alignment with links 23, will now be pushed farther open by the return movement of these links. When the plunger 7 has reached the end of this structure 115 in the right hand portion of the cylinder, the doors will be at the limit of the movement and the roller 18 will again reach the end of the rod 19 and be again moved by spring 16^b to its position as shown in Fig. 2. In this position, the rod 15 is moved to central or neutral position. The inlet valve for the cylinder is closed and the exhaust valves are open, and the valve plunger rod 18 120 and bar 19 are locked in position with the doors fully open. The doors will remain in this position until the button 14 is again pressed and the operation repeated. A closing movement of the doors will take place 125 130.

- exactly the same as with the opening movement, the doors swinging past the dead center and actuating the bell crank 16 and rod 15, as above described.
- 5 With the invention herein disclosed it will thus be seen that a single solenoid 12 is used in place of the double solenoid shown in the above referred to patent. It will also be understood that where the double hinge 10 doors have been shown, the device would work equally as well with a single hinge door, which door would operate past the dead center in the manner similar to that described for the doors herein illustrated.
- 15 From the above description it will be apparent that when the air motor comprising plunger 7 and piston 8 is initially operated, the doors will be initially moved with the maximum turning force and with the full 20 power of the motor. This turning force will decrease owing to the change in the leverage until the doors reach the dead center position in alignment with the links in 25 partially open position. After swinging past this position and the motor being reversed, the turning force will then increase from the dead center position as the doors approach fully open position owing to the change in leverage of the links. As the doors 30 approach completely open position the motor is cushioned at the end of its stroke so that the doors are brought positively and gently into the fully open position. In closing the doors, the operations will be reversed 35 and the doors will be positively moved to closed position, at which time the motor will be cushioned.
- From the above description it is seen that applicant has provided a highly efficient 40 door opening and closing mechanism and one which can be readily and instantly controlled. By means of the check valve structure shown in Fig. 3, the doors are brought gently to open and closed position, and a 45 jar or shock usually incident to such movement is eliminated.
- While the device is shown disposed in a horizontal position, and suspended from above the doors, it will be understood that 50 the same may be equally well used in a vertical position and can also be used to operate doors other than doors swinging upon vertical pivots.
- It will also be understood that various 55 changes may be made in the form, details and arrangement of the device without departing from the scope of applicant's invention, which, generally stated, consists in the matter shown and described and set forth 60 in the appended claims.
- What is claimed is:
1. A door opening and closing mechanism having in combination a means mounted for reciprocation, links pivoted to the same and 65 pivoted at their other end to hinged doors, a
- motor propelled plunger rod for reciprocating said means and a reversing means for said plunger rod and motor operated by the momentum of the doors as they swing past the dead center position in alignment with 70 said links.
2. A device of the class described having in combination a movable member, links pivoted to the same and diverging therefrom and pivoted at their other ends to hinged 75 doors, means for moving said member in one direction to swing the doors into dead center position in alignment with said diverging links, valve mechanism for controlling said means, and a reversing mechanism for said 80 valve mechanism operated by the doors as they swing past the dead center position by their acquired momentum.
3. A door opening and closing mechanism having in combination reciprocating means 85 pivoted to said doors, means for locking said reciprocating means in position with the doors closed or fully open, means for moving said reciprocating means, a valve mechanism for controlling said latter means, an 90 electrical means for opening the valve mechanism in one direction to move the locking means from locking position and to actuate the moving means in one direction, said valve mechanism being moved into position 95 to actuate the moving means in the other direction by mechanism actuated by the inertia or momentum of the doors.
4. A device of the class described having in combination a crosshead, links pivoted 100 thereto and diverging therefrom and pivoted at their other ends to hinged doors, a cylinder, a plunger movable therein, a plunger rod connected to said plunger and to said cross head, a valve mechanism for controlling a supply of motor fluid to said cylinder, 105 electrical means for actuating said valve in one direction to admit fluid to one side of said plunger and move the crosshead to swing the doors to partially open position, 110 and mechanical means operated by the inertia of said partially open doors to move the valve mechanism in another direction to admit fluid on the other side of the plunger 115 which will move the crosshead and plunger in the other direction, whereby the pivoted links will move the doors to fully open position.
5. A device of the class described having in combination a movable crosshead, links 120 pivoted thereto and diverging therefrom and pivoted at their other ends to hinged doors, a longitudinally movable plunger rod connected to said crosshead, locking means for holding said crosshead in position with 125 the doors either open or closed, means for moving said plunger rod in either direction, valve means for controlling said latter means, electrically operated means for actuating said valve mechanism, to unlock said 130

- locking means and to cause said moving means to be actuated in one direction, and mechanical means comprising a bell crank lever connected to said valve mechanism actuated by the movement of said doors to move said valve mechanism to cause the moving means to be actuated in reverse direction to move said crosshead and to complete the opening of said doors.
10. 6. A device of the class described having in combination, a reciprocating member, means connected thereto and also connected to hinged doors, locking means for holding said member in stationary position with the doors either fully closed or fully open, a motor for reciprocating said member, motor controlling mechanism, means for moving said motor controlling mechanism to one position so that the motor will move said member in one direction, and means operated by the movement of the doors to move said controlling mechanism to another position so that the motor will move said member in another direction to complete the opening movement of said doors.
15. 7. A device of the class described having in combination a reciprocating member, links pivoted to said member and diverging therefrom and pivoted at their other ends to hinged doors, an air cylinder, a plunger movable therein, a plunger rod connected thereto and to said reciprocating member, a bar connected to said plunger rod and movable therewith, valve mechanism movable to positions to admit air into either end of said cylinder, a pivoted bell crank lever, a roller carried thereby, means for holding the lever in position with the roller contacting the end of said bar to hold the same and the reciprocating member in stationary position, a connection between said lever and the valve mechanism, means for moving the valve mechanism to one position to admit air into one end of the cylinder and to move said lever and roller through the above mentioned connection, and means on the end of said bar for moving said lever and roller by the inertia of the partially open doors to move the valve mechanism to position to admit air into the other end of the cylinder to move the reciprocating member in the opposite direction whereby the doors are moved to fully open position by the said links.
20. 8. A device of the class described comprising a fluid cylinder, a plunger therein, a plunger rod connected thereto, a member connected to said plunger rod, a bar carried by said member and plunger rod and movable therewith, valve mechanism for controlling the supply of fluid to said cylinder, a pivoted bell crank lever having means in one end thereof normally engaging the end of said bar to hold the same and said plunger rod in stationary position, a connection between said lever and said valve mechanism, means for moving said valve mechanism to admit fluid into one end of said cylinder and to swing said lever and means thereon out of engagement with the end of said bar, spring means for holding said lever in normal position, and means on the other end of said bar for swinging said lever and means thereon to move the valve mechanism to position to admit air into the other end of said cylinder, said latter means being actuated by the inertia of said member.
25. 9. A device of the class described comprising a fluid cylinder, a plunger movable therein, a plunger rod connected to said plunger and movable therewith, valve mechanism for controlling the supply of fluid to said cylinder, and a locking and controlling means for said plunger and plunger rod comprising a bell crank lever having a roller at one end thereof, and a rod connecting the other end thereof to said valve mechanism, a bar connected to said plunger rod and movable therewith, spring means for holding said lever with the roller normally engaging the end of said bar, said bar being beveled at its other end to move said roller upwardly when the same is in engagement therewith.
30. 10. A door opening and closing mechanism having in combination a fluid cylinder, a plunger therein, a plunger rod connected to said plunger, a member connected to said plunger rod and the hinged doors, valve mechanism for controlling the supply of fluid to said cylinder, air conductors between said valve mechanism and said cylinder comprising a member spaced from one end of said cylinder and having a port therein communicating with said cylinder and said air conduit, a cylinder head connected to said conduit, a port in said cylinder head, a check valve therein, a smaller port connecting said conduit to the check valve chamber, and means for adjusting the size of said smaller port.
35. 11. The combination with the valve mechanism, cylinder and plunger rod of an air motor, a locking and controlling mechanism comprising a flat bar connected to said plunger rod and movable therewith, a pivoted bell crank lever having a roller at one end thereof, spring means for normally holding said roller in position with said roller in engagement with the end of said bar, connections between the other end of said bar and the valve mechanism for swinging said roller out of engagement with the end of said bar whereby the roller will contact with the lower edge of said bar when the same is reciprocated, said bar having its other end beveled whereby the roller will be raised by the said spring means and said beveled portion of the bar to contact

with the top edge of said bar when the bar is moved in a reverse direction.

12. A door opening and closing mechanism having in combination a reciprocating member, links pivoted to said member, and diverging therefrom and pivoted at their other end to swinging doors, and electrically controlled air operated means to reciprocate said member in one direction to 10 partially open said doors and in the opposite direction to completely open said doors, said doors moving the said links past the position in which the doors are partially opened by their momentum.

15 13. A door opening and closing mechanism having in combination a reciprocating crosshead, links pivoted to the same and diverging therefrom and pivoted at their other ends to hinged doors, and means for 20 reciprocating said crosshead in one direction to swing the doors into substantial alignment with the links, substantially into a dead center position and in the other direction to complete the opening or closing 25 movement of said doors said links being carried past said dead center position by the momentum of said doors.

14. A door opening and closing mechanism having in combination a reciprocating means, members pivoted thereto and to hinged doors, and means for moving said reciprocating means, first in one direction to move the doors to partially open position, and then in the opposite direction to completely open or close the same said members being carried past their position when the doors are in partially open position by the inertia of said doors.

15. A door opening mechanism having 40 in combination a means mounted for movement in reverse directions, means pivoted thereto and also pivoted to hinged doors, a motor for moving said first mentioned means in one direction to partially open 45 said doors, and in the other direction to completely open said doors, said second mentioned means being moved past its position in which the doors are partially open by the momentum of said doors.

50 16. A door opening mechanism having

in combination a member mounted for reverse movements, means connected thereto and to hinged doors by a flexible connection, a compressed air motor connected to said member for moving the same in one direction to partially open said doors and in a reverse direction to completely open said doors, said means being movable past its position in which the doors are partially open by the momentum of said doors. 60

17. The structure set forth in claim 16, and a remote electrical control for said compressed air motor.

18. A door operating mechanism having in combination a member movable in opposite directions, means pivoted thereto and to swinging door and an air motor for moving said member in one direction to partially open the doors, said parts being so constructed and arranged that the doors 70 are initially open with a maximum turning force which decreases until the doors are partially open in a dead center position, said doors swinging the said means past said dead center position by their acquired 75 momentum, said motor then moving the member in the opposite direction to completely open said doors, the turning force increasing from a dead center position until the doors are fully open, and means for 80 cushioning the doors as the same reach fully open position.

19. The combination with a hinged door comprising a plurality of hinged sections, of an operating mechanism comprising a 85 reciprocating means and a link pivoted to said means and to one of said sections adjacent its outer hinged edge whereby the door can be partially opened or partially closed and the door partially folded or unfolded 90 by one stroke of said reciprocating means, and completely opened or closed and completely folded or unfolded, respectively, by the opposite stroke of said reciprocating means, said folding sections preventing 95 interference of said link and door.

In testimony whereof I affix my signature.

DAVID W. CAMPBELL.
